UNITED STATES PATENT OFFICE

161,537

TRANSMISSION HOUSING FOR A SELF-POWERED TRACTOR UNIT

Jacob A. Ronning, Minneapolis, Minn.

Application March 25, 1950, Serial No. 8,765

Term of patent 14 years

(Cl. D40—1)

To all whom it may concern:

Be it known that I, Jacob A. Ronning, a citizen of the United States, residing at Minneapolis, in the county of Hennepin, and State of Minnesota, have invented a new, original, and ornamental Design for a Transmission Housing for a Self-Powered Tractor Unit, of which the following is a specification, reference being had to the accompanying drawings, forming part thereof.

Referring to the drawings:

Fig. 1 is a view in perspective of a transmission housing for a self-powered tractor unit, showing my novel design;

Fig. 2 is a view in side elevation as seen from the left to the right with respect to Fig. 1;

Fig. 3 is a view in side elevation as seen from the right to the left with respect to Fig. 1;

Fig. 4 is a view in front elevation; and

Fig. 5 is a view in plan.

The dotted lines in Fig. 1 indicate a self-powered tractor unit and merely illustrate the

type of unit to which my novel transmission housing is applied.

I claim:

The ornamental design for a transmission housing for a self-powered tractor unit, as shown and described.

JACOB A. RONNING.
